UNITED STATES PATENT OFFICE.

EPHRAIM L. HURD, OF OKLAHOMA CITY, OKLAHOMA.

MECHANICAL MOVEMENT.

Application filed May 12, 1924. Serial No. 712,545.

This invention is a division in part of my co-pending application for patent on continuous washing machine filed April 28, 1924, Serial No. 709,616. In my co-pending application I have shown a continuous washing machine which is made up of sections and which has a rotor disposed therein. The clothes containers are adapted to be carried by the rotor and to be moved through the rotor by a mechanism mounted in a single casing. The rotor is also turned in both directions by means of the same mechanism. This mechanism is disclosed in my co-pending application, but is not claimed. The present invention consists of this special mechanism for rotating the rotor and for moving the containers through the rotor.

An object of my invention is to provide a mechanism which is adapted to convert the rotary movement into an intermittent rotary movement, and which has manually controlled means for stopping the intermittent rotary movement.

A further object of my invention is to provide a device of the character described which has an arm that is adapted to be swung about its pivotal point and which is actuated by means of a rotating shaft through the use of cams.

A further object of my invention is to provide a device of the character described which has manually controlled means for stopping the rocking of the arm and yet permit the shaft to continue to rotate.

Other objects and advantages will appear in the following specification, and the novel features of the invention will be particularly pointed out in the appended claims.

My invention is illustrated in the accompanying drawings forming part of this application, in which

Figure 1 is a plan view of the device shown operatively applied to the clutch which is used in connection with the laundry machine, which is described in my co-pending application.

Figure 2 is a transverse section of the device substantially along the line 2-2 of Figure 1.

Figure 3 is a plane view of the device with a portion of the cover removed.

Figure 4 is a section along the line 4-4 of Figure 3, and

Figure 5 is a diagrammatic view of a portion of the device.

In the drawings I have shown a driving mechanism for the rotor and container mover. The rotor and container mover form the subject matter of my co-pending application Serial No. 709,616 filed April 28, 1924. This mechanism is mounted in a casing 1. A shaft 2 is rotatably carried by bearings 3 and 4 and is provided with a pulley 5.

A worm 9 is mounted on the shaft 2 and is rotated by the shaft. A shaft 10 is carried by the casing 1 and carries a worm gear 11 that is in mesh with the worm 9. It will be noted from Figure 2 that the gear 11 is mounted upon a shank 12 of a clutch member 13. The clutch in turn is mounted upon a sleeve 14, the sleeve being rotatably disposed upon the shaft 10. The clutch 13 has a gear 15 that is in mesh with an idler gear 16. The gear 16 in turn is mounted upon the stub shaft 17 which is carried by a support 18. A second gear 19 is mounted upon the stub shaft 17 and is in mesh with a gear 20. The gear 20 is secured to a shaft 21 which is mounted in the casing 1. A gear 22 is loosely mounted upon the shaft 21 and is in mesh with an idler gear 23, the idler gear being carried by the casing 1 (see Figure 3).

A gear 24 is loosely mounted on the shaft 10 and is provided with a cam 25, see Figure 5. It will be seen from the construction thus far described that when the shaft 2 is rotated, it will not rotate the shaft 10 but will rotate the gear 24 upon the shaft 10. A second clutch member 26 is keyed to the shaft 10 and is adapted to engage with the clutch member 13. The means for moving the clutch member 26 is clearly shown in Figure 2, and comprises a fork 27 that is slidably disposed upon guide rods 28 that are carried by the casing 1. The fork is received in a groove 29 in the clutch 26, whereby movement of the fork 27 on the rods 28 will move the clutch member 26 into or out of engagement with the clutch member 13.

The means for moving the fork 27 comprises a roller 30 that is kept in contact with the cam 25 by means of springs 31. The springs 31 are disposed in recesses in the fork 27 and bear against the casing so as to move the fork away from the casing, see Figure 2. It will be apparent from this construction that as the gear 24 is rotated by the shaft 2, the fork 27 will be moved so as to throw the clutch member 26 into or out

of engagement with the clutch member 13. When in engagement, the shaft 10 will be turned by the worm gear 11.

The means for rotating the rotor (not shown) in both directions is accomplished by the mechanism shown in the drawings. This mechanism comprises an arm 53 that is secured to a shaft 54, the shaft 54 being carried by the casing 1. A second arm 55 is secured to the lower end of the shaft 54 and carries two rollers 56 at its free ends. The rollers 56 are adapted to contact with cams 57 and 58 that are mounted upon the gear 20. A rotation of the gear 20 will cause the arm 55 and the arm 53 to rock. In Figure 1 I have shown a link 59 that is connected to the free end of the arm 53 and has its free end connected to a lever 60. The free end of the lever 60 is mounted in a collar 61 and is adapted to move the collar on a shaft 62. A collar is connected to two clutches 63 and 64 that are keyed to the shaft 62 and are adapted to be thrown into engagement with clutch members 65 and 66 respectfully. Pulleys 67 and 68 are secured to the clutch members 65 and 66 and are connected to a drive (not shown). The pulley 68 is driven in the reverse direction to that of the pulley 67. It will be apparent from this construction that the shaft 62 will be rotated in both directions by means of clutches 63 and 64.

In case it is desired to stop the arm 53 from rocking, the operator may disconnect the arm 53 from the shaft 54 whereby the arm will not be actuated and will not move the clutches 63 and 64 into and out of operative engagement with the clutch members 65 and 66. In Figure 2 the arm 53 is shown loosely mounted upon the shaft 54 and supported by a supporting member 144. The supporting member is rigidly secured to the shaft 54 and is provided with a notch 145. An arm 148 is carried by the arm 53 which in turn carries an actuating arm 150. The arm 150 is adapted to swing a link 149, which is operatively connected to a link 146 by means of a rod 147. A latch 145' is operatively connected to the link 146, by a pin 146' and is adapted to be swung into the notch 145, when the link 149 is swung from the dotted line position into the full line position. If it is desired to disconnect the arm 53 from the supporting member 144, it is merely necessary to swing the actuating handle 150 so as to release the latch 145' from the notch 145.

I have also shown in Figures 3 and 4 manually controlled means for stopping the rotation of the shaft 10. The casing 1 carries an arm 151 which is connected to a shaft 152. A lever having arms 153 and 154 is secured to the shaft 152 and is adapted to be swung when the control handle 151 is swung. The free end of the arm 153 has a pin which

is slidably received in a groove 158 of a clutch member 157. The arm 154 is adapted to be swung toward the gear 24, when the handle 151 is actuated and to contact with the edge of a stop member 155 that is carried by the gear 24. When the handle 151 is moved into the position shown in Figure 1 it will cause the arm 153 to release the clutch member 157 from the clutch member 156, and thus disconnect the gear 22 from the shaft 21. The gear is loosely mounted upon the shaft and the clutch member 157 is keyed to the shaft. While the arm 153 is releasing the clutch member 157 the arm 154 is being swung into engagement with the stop member 155 and stops the gear 24 from further rotation. In this way the shaft 10 is brought to an abrupt stop.

From the foregoing description of the various parts of the device, the operation thereof may be readily understood. When the pulley 5 is rotated by any means, (not shown) it will rotate the shaft 2 and will also rotate the gear 24 through the medium of the gears 11, 16, 19, 20, 22, and 23. When the gear 24 is rotated it will cause the fork 27 to be moved on the rods 28, and to throw the clutch member 26 into and out of engagement with the clutch member 13. As heretofore stated the clutch member 26 is keyed to the shaft 10 and when in engagement with the clutch member 13 it will rotate the shaft 10. The rotation of the gear 24 continues as long as the pulley 5 is rotated and as long as the clutch member 157 is in engagement with the clutch member 156.

In case the operator wishes to stop the rotation of the gear 24, he merely has to move the arm 151 so as to cause the arm 153 to move the clutch member 157 out of engagement with the clutch member 156. This operation disconnects the gear 22 from any driving connection with the shaft 2. The handle 151 when swung also swings the arm 154 toward the gear 24 and brings the arm 154 into contact with the stop member 155, whereupon the gear 24 is brought to an abrupt stop. When the gear 24 rotates, the fork 27 will stop from moving and will therefore stop connecting and disconnecting the clutch member 26 with the clutch member 13. The shaft 10 will therefore stop from rotating even though the shaft 2 still rotates.

The arm 53 can be stopped from movement if desired, this being accomplished by swinging the handle 150 (see Figure 2) so as to move the link 149 into the dotted line position. The arm 53 is operatively connected to the shaft 54 by means of the latch 145'. The arm 53 will therefore be disconnected from the shaft 54 since the latch 145' is swung out of the notch 145 in the castings 144.

The arm 53 is normally rocked by means

of the arm 55 which has two rollers 56 that contact with the cams 57 and 58 on the gear 20. As the gear 20 is rotated by means of the shaft 2, the cams 57 and 58 will rock the 5 shaft 54 and also the arm 53.

The mechanism for intermittently rotating the shaft 10 and for rocking the arm 53 is combined within one casing and is very compact in construction. Furthermore the 10 casing has novel manually controlled means for instantly stopping the rotation of the shaft 10 and also the movement of the arm 53 if desired. The device is simple in construction is durable and efficient for the purpose intended and provides a novel control 15 box for the laundry machine which is explained in my co-pending application.

I claim:

1. A mechanical movement comprising a 20 casing, a driving shaft, a driven shaft, a gear loosely mounted on said driven shaft, means for connecting and disconnecting said gear to and from said shaft, said means comprising a second gear loosely mounted on 25 said driven shaft, a cam carried by said second named gear, a clutch mounted on said driven shaft, a clutch arm actuated by said cam, said clutch connecting and disconnecting said first named gear to and from said driven shaft, said second named gear being 30 operatively connected to said driving shaft.

2. A mechanical movement comprising a

casing, a driving shaft, a driven shaft, a gear loosely mounted on said driven shaft, means for connecting and disconnecting said gear to and from said shaft, said means comprising a second gear loosely mounted 35 on said driven shaft, a cam carried by said second named gear, a clutch mounted on said driven shaft, a clutch arm actuated by said cam, said clutch connecting and disconnecting said first named gear to and from said driven shaft, said second named gear being 40 operatively connected to said driving shaft, and means for disconnecting said second 45 named gear from said driving shaft.

3. A mechanical movement comprising a casing, a driving shaft, a driven shaft, a gear loosely mounted on said driven shaft, means for connecting and disconnecting said gear to and from said shaft, said means comprising a second gear loosely mounted 50 on said driven shaft, a cam carried by said second named gear, a clutch mounted on said driven shaft, a clutch arm actuated by said cam, said clutch connecting and disconnecting said first named gear to and from said driven shaft, said second named gear being 55 operatively connected to said driving shaft, and means for disconnecting said second named gear from said driving shaft, said means bringing said second named gear to an abrupt stop. 60

EPHRAIM L. HURD.
